UNITED STATES PATENT OFFICE.

THEODORE R. TIMBY, OF WASHINGTON, DISTRICT OF COLUMBIA.

PROCESS OF AND APPARATUS FOR AGING WINES, SPIRITS, OR OTHER LIQUORS.

SPECIFICATION forming part of Letters Patent No. 496,759, dated May 2, 1893.

Application filed November 14, 1892. Serial No. 451,983. (No model.)

To all whom it may concern:

Be it known that I, THEODORE R. TIMBY, a citizen of the United States, residing at Washington, in the District of Columbia, have invented certain new and useful Improvements in Processes of and Apparatus for Aging Wines, Spirits, or other Liquors, of which the following is a specification.

In Letters Patent of the United States No. 485,999 and No. 486,000, granted to me the 8th of November, 1892, for processes of and apparatus for aging wines, spirits or other liquors, I have described a mode of treatment under which the liquor, in bulk, as for example in barrels in which it is commonly stored, is subjected to rapid mechanical vibration produced by the movement of railway cars on a track, preferably notched or recessed, and causing a sustained tremulous action which is diffused through the body of the liquor. I have discovered that the action upon the liquor can be increased and the desired change expedited by subjecting it to a combined tremulous action as already described, and a lateral rocking or oscillating movement which serves to constantly change the surface of the liquor exposed to the air, in the barrels or other packages and thus accelerates the diffusion of the atmosphere or oxidizing gas through the body. I prefer to effect this operation by constructing an endless railway track with one or both rails undulating and when undulations are made in both rails having the elevations in one rail opposite the depressions in the other, so as to apply a lateral oscillatory or rocking movement to trucks running thereon and to the load carried thereby. If preferred a similar effect may be produced by means of trucks running on a level track and cradles mounted on the truck platforms so as to rock or swing, which movement in conjunction with the progressive motion and the tremulous action produced thereby operates on the liquor in a very rapid and effective manner.

It will be understood that the tremulous action sought is produced by relative progressive movement between the carrying trucks and the track and hence it is immaterial whether the trucks run on the track or the track runs beneath the trucks or both. For driving the track beneath the trucks

mounted thereon a turntable may be employed, driven by suitable gearing or belt.

In the accompanying drawings:—Figure I 55 a perspective view of an apparatus illustrating the invention consisting of an endless revolving track constructed with undulating rails, and springless trucks running thereon driven by an endless cable, and on which the 60 liquor is stored in barrels. Fig. II is a plan illustrating the use of a turntable carrying the undulating rails, and stationary trucks mounted thereon beneath which the rails run. Fig. III is a vertical section of the same. Fig. 65 IV is a detail elevation on a larger scale of a part of the track shown in Fig. I, for the purpose of illustrating more clearly the opposed elevations and depressions in the opposite rails of the track. Fig. V is a partial plan of 70 the same. Figs. VI and VII are vertical sections of the same showing the extreme inclination of the trucks in opposite directions.

In carrying out my invention I prefer to employ an endless railway track 1 as illustrated in Fig. I mounted on a solid unyielding foundation 2 and having the rails notched or recessed as indicated by dotted lines at 3 in Figs. IV and V for the purpose of imparting a jarring motion to the springless trucks for 80 running thereon and thereby imparting a stronger tremulous motion through the body of the liquor in the barrels 5 which are loaded or stored upon the said trucks as described in Letters Patent No. 485,999, granted to me 85 the 8th day of November, 1892.

The notched or recessed track is not essential to my present invention though it operates very advantageously in conjunction therewith.

In my present improvement I construct one or both of the track rails with undulations so as to impart an oscillating or rolling motion to the trucks and their load of liquor as illustrated in Figs. I, III, VI and VII. The undulations are exaggerated in the drawings and are indicated particularly in the detail diagram Fig. IV. They are shown much shorter, deeper and more abrupt than they are required to be. In practice one wave in each 100 fifty feet of track will suffice to impart a rolling motion simulating that to which liquor is subjected on ship-board, which is well-known to be highly efficacious in accelerat-

ing the aging of liquors. The undulations may be produced by waving both rails of the track, the elevations in one rail being directly opposite the depressions of the other as shown 5 in the drawings, or the effect may be produced by means of one rail only of the pair. In practice a variation of two inches in the height 10 of the rails is believed to be sufficient but this may be increased or the undulations brought nearer together when the motion imparted to the trucks is to be comparatively slow.

The variation of the surface level of the liquor with reference to the barrels and truck 15 platforms, under the rolling motion is indicated by dotted lines in Figs. III, VI and VII. To increase the effect of the rolling motion and expose a larger surface of liquor to the air the barrels are not quite filled with liquor. 20 The trucks may be driven by any suitable means. For illustration I have shown an endless cable 9 carried over vertical and horizontal guiding sheaves 12, 12^a, 13, 13^a to and from any suitable cable-driving mechanism not 25 here shown. Suitable mechanism for this purpose is shown and described in my patent No. 485,999, hereinbefore referred to. I have also shown suitable cable seats 10 upon the sides 30 of the trucks and suitable guiding sheaves 26 on which the cable runs in the intervals between the cars or trucks. I have also indicated a switch 11 by means of which the trucks may be run on and off the endless track as required. In practice the endless track may be 35 filled with trucks or otherwise as circumstance requires and it is not necessary that all the trucks should be provided with cable seats 10.

I have illustrated in Figs. II and III the use 40 of a turntable 36 for driving the track 1 beneath the trucks 4 which may be held stationary by means of an abutment 40 adapted to be thrown up when it is required to run the cars off the turntable. A switch 11 is used as before for running the trucks on and 45 off the turntable. The turntable may thus be

completely filled with loaded trucks if required. As each truck is run on by the switch 11 it moves around as illustrated at 4^a and 4^b in Fig. II until it is stopped by the rear end 50 of the series of trucks 4 bearing against the abutment 40. Pinion 38 and gear wheel 39 are shown as suitable means for driving the turntable 36. I have also shown customary antifriction balls 37 for the turntable to run on.

The extent and proximity of the undulation 55 in the track rails are much exaggerated in Fig. III, for clearness of representation.

Having thus described my invention the following is what I claim as new therein, and 60 desire to secure by Letters Patent—

1. The process of aging wines, spirits and other liquors which consists in storing the same on suitable trucks or cars, producing progressive relative movement between said trucks and the tracks on which they are 55 mounted to cause a diffused tremulous action through the liquor and imparting a simultaneous lateral rolling or oscillating movement to the body of liquor, as explained.

2. In an apparatus for aging wines, spirits 70 and other liquors the combination of one or more trucks on which the liquor is stored and a railway track one rail of which projects at intervals above the level of the other, whereby lateral oscillation is imparted to the truck 75 platforms and to the liquor stored thereon, as explained.

3. In an apparatus for aging wines, spirits and other liquors the combination of one or 80 more trucks on which the liquor is stored and a track constructed with undulating rails with the elevations in one rail opposite the depressions in the other, whereby lateral oscillation is imparted to the trucks running on said track as explained.

THEODORE R. TIMBY.
